Primary Examiner — Robert M Spear*Assistant Examiner* — Marissa J Cash(57) **CLAIM**

The ornamental design for the safety cap for rebar, as shown and described.

DESCRIPTION

FIG. 1 is a bottom plan view of the safety cap for rebar; FIG. 2 is a right side view of the safety cap for rebar, the left side being a mirror image;

FIG. 3 is a top perspective view of the safety cap for rebar; and,

FIG. 4 is a bottom perspective view of the safety cap for rebar. The broken line portion of FIG. 1 depicting unclaimed subject matter forms no part of the claimed design.
